KERATIN EXFOLIATIVE COMPOSITIONS

William O. Elson, Chicago, Ill., assignor to The Kendall Company, Boston, Mass., a corporation of Massachusetts

No Drawing. Application January 10, 1951,
Serial No. 205,435

21 Claims. (Cl. 167—61)

1

This invention relates to the treatment of the skin and specifically relates to compositions of matter useful in the treatment and/or the removal or other elimination of calluses, corns and other undesirable keratin and keratinaceous matter. The novel compositions of this invention are applied to skin on living tissue for the purpose of causing sloughing off of the keratin of the treated skin. Such compositions will hereinafter be designated as keratin exfoliative compositions.

Present-day compositions used for the treatment of calluses and corns, for example, the ordinary corn pad, contain a keratin exfoliating agent—salicylic acid in most instances—mixed with a plastic composition from which the salicylic acid is released when the composition is in contact with the skin.

The compositions of this invention contain novel keratin exfoliating agents mixed with carriers of the type hereinafter described and provide keratin exfoliative activity equal, and in some instances superior, to that obtained by present-day salicylic acid compositions in the treatment of corns and the like. Many compositions of this invention have been found to produce more nearly complete keratin exfoliation and with reduction in the time necessary for treatment.

Compositions of this invention comprise an admixture of a substantially non-volatile organic film-forming vehicle with an acid which falls within the group of organic acids having acid factors, as hereinafter defined, within the narrow range of 1.5 to 3.5, and lipid coefficients, as hereinafter defined, not greater than 5, other than salicylic acid.

The acid factor of a substance is defined, for the purposes of this invention, as the pH of a saturated water solution of a substance at 37° C. Originally hot and cold solutions are agitated at 37° C., for 24 hours, the pH of each is then determined by usual methods, and the two pH's are averaged.

The lipid coefficient of a substance is defined for the purpose of this invention as the ratio at 37° C. of the solubility of the substance in water to the solubility of the substance in benzene. To determine the lipid coefficient, excess amounts of the compound are placed in two pairs of flasks containing respectively hot and cold distilled water and hot and cold CP benzene. The flasks are then agitated at 37° C. for 24 hours to obtain completely saturated solutions in the two liquids. Exactly 20 cc. each of the four saturated solutions are heat dried in weighing bottles at approximately 50° C. until no liquid remains. They are then further dried at approximately 100° C., until constant weight is obtained. The residue-containing bottles are cooled in a desiccator and weighed. The gain in weight of the respective bottles represents the weight of dried material

2

soluble in equal volumes of water and benzene respectively.

Lipoid coefficient K=

mgm./20 cc. water solution at 37° C.
mgm./20 cc. benzene solution at 37° C.

The average residue in 20 cc. from originally hot and cold solutions is used in the above formula.

- 10 As an alternative method, after obtaining completely saturated solutions, exactly 20 cc. of each of the four saturated solutions are pipetted into clean 250 cc. flasks. These are diluted with 50 cc. of ethyl alcohol and titrated with standardized 1⁶ N alcoholic potassium hydroxide with phenolphthalein as the indicator. The milligrams of acid per 20 cc. are calculated by the usual method whereupon the lipoid coefficient is determined as above.
- 20 So far as I am aware, I am the first to discover not only that these two apparently unrelated physico-chemical properties are of controlling significance in the determination of keratin exfoliative activity but that when both the acid factor and lipoid coefficient of an acid fall within limited narrow ranges, it can be counted upon, when included as the active ingredient of compositions of this invention, to provide sufficient keratin exfoliative activity for successful keratin exfoliation, just as salicylic acid can be so counted upon, since it has both acid factor and lipoid coefficient in the proper ranges.

- 30 Not only is each of these properties important but both are essential since clinically acceptable keratin exfoliative activity is found only in substances simultaneously possessing both of these properties. In my experience, those substances possessing both properties have always produced satisfactory clinical keratin exfoliation, while those substances possessing one but lacking the other, as well as those lacking both, have not produced satisfactory clinical keratin exfoliation.

- 40 Because of the requirements simultaneously of a definite, narrow lipoid coefficient range and a specific, narrow acid factor range, the field of keratin exfoliating agents is now distinctly segregated, and viewed from the standpoint of all conceivable chemicals is very limitedly confined to certain organic acids. Nevertheless, within that limited field, the number of potentially useful acids is relatively large, though most of them are unavailable commercially, others are rare.

- 50 Among substances having proper acid factor and lipoid coefficient values and hence acceptable keratin exfoliative activity are aromatic ethers and thioethers of aliphatic acids including the entire group of alpha linked phenoxy and phenylmercapto aliphatic acids having less than six carbon atoms in each of one or more aliphatic acid

radicals and with or without one or more halogen or alkyl (below pentyl) groups replacing up to

not more than 3 of the hydrogens of the phenyl radical, examples of which are:

Structural Formula	Name	Lipoid	pH Acid Factor
	phenoxyethanoic acid.....	0.4	2.1
	phenylmercaptoethanoic acid.....	0.05	2.4
	2-phenoxypropanoic acid.....	0.06	2.4
	2-phenoxybutanoic acid.....	0.01	2.4
	2-chlorophenoxyethanoic acid.....	0.4	2.8
	4-chlorophenoxyethanoic acid.....	0.4	2.7
	2,4-dichlorophenoxyethanoic acid.....	0.06	2.8
	2-phenoypentanoic acid.....	0.01	2.9
	2,4,5-trichlorophenoxyethanoic acid.....	0.5	3.3
	4-tert-butylphenoxyethanoic acid.....	0.04	3.0

Structural Formula	Name	Lipoid	pH Acid Factor
	4-methylphenoxyethanoic acid.....	0.4	2.5
	2-methylphenoxyethanoic acid.....	0.4	3.2
	2,5-dimethylphenoxyethanoic acid.....	0.5	3.2
	1,4-phenylene-di-ethanoic acid.....	5.	3.1
	2,3-diphenoxylbutanedioic acid.....	0.06	2.9
	diphenoxylethanoic acid.....	0.01	2.4

Other phenoxy and phenylmercapto aliphatic acids which have lipoid coefficients and acid factors within the required range are 2-phenylmercapto propanoic acid, 2-phenylmercapto butanoic acid, 2-phenylmercapto pentanoic acid, 3-phenoxy propanoic acid, 3-phenylmercapto propanoic acid, 2-chlorophenylmercaptoethanoic acid, 4-chlorophenylmercaptoethanoic acid, 2,4-dichlorophenylmercaptoethanoic acid, 2,4,5-trichlorophenylmercaptoethanoic acid, 2-methylphenylmercaptoethanoic acid, 4-methylphenylmercaptoethanoic acid, 4-t-butylphenylmercaptoethanoic acid.

45 acid, 2,5-dimethylphenylmercaptoethanoic acid, 3,4-dimethylphenylmercaptoethanoic acid, 1,4-phenylene-di-mercaptoethanoic acid, diphenylmercaptoethanoic acid, 2,3-diphenylmercapto butanedioic acid, o-methoxyphenoxyethanoic acid, o-ethoxyphenoxyethanoic acid, o-methoxyphenylmercaptoethanoic acid and o-ethoxyphenylmercaptoethanoic acid.

50 Another group of suitable substances are phthalic half esters such as methyl acid phthalate, propyl acid phthalate and butyl acid phthalate.

Structural Formula	Name	Lipoid	pH Acid Factor
	methyl acid phthalate.....	0.2	2.0
	n-propyl acid phthalate.....	0.001	2.4
	n-butyl acid phthalate.....	0.004	2.9

Another group of substances possessing the significant properties are benzoic acid derivatives such as 2-methoxybenzoic acid, 2-methylbenzoic acid, 2-fluorobenzoic acid and thiosalicylic acid.

Structural Formula	Name	Lipoid	pH Acid Factor
	2-methylbenzoic acid.....	0.004	3.1
	2-methoxybenzoic acid.....	0.1	2.8
	2-fluorobenzoic acid.....	0.1	2.5
	thiosalicylic acid.....	0.1	3.1

The number of carbon atoms in all of the above substances is more than seven whenever the number of non-cyclic oxygen atoms is exactly three.

Other cyclic compounds in the proper ranges are heterocyclic, examples being thiophene-2-carboxylic acid, 2-furoic acid and 2-furalpropenic acid.

The best agents have lipoid coefficients of .4 to .001 and acid factors of about 2.1 to 2.5.

An illustration of how certain only of a number of closely related acids are useful is afforded by an examination of homologous series of compounds.

As revealed in Table I, phthalic acid has an acid factor in the proper range but the lipoid coefficient is outside the range. It has no appreciable keratin exfoliative activity. Surprisingly, methyl acid phthalate, which differs structurally only by the replacement of the hydrogen of one of the carboxy groups by a methyl group, has such increased water solubility and benzene solubility that it falls within the proper range with respect to both acid factor and lipoid coefficient. It will be noted that the significant factors are in the proper ranges, but they are not at optimum values, so optimum clinical results would not be expected.

Next, n-propyl acid phthalate, which involves only the replacement of the methyl by a propyl group, has near optimum values for acid factor and lipoid coefficient and has excellent clinical activity.

Next, n-butyl acid phthalate, involving replacing propyl by a butyl group carries the acid factor beyond the optimum but still in the range. This compound is clinically better than the methyl homolog but not so good as the propyl homolog.

Structural Formula	Name	Lipoid	pH Acid Factor
	thiophene-2-carboxylic acid.....	0.1	2.6
	2-furoic acid.....	3.5	1.9
	2-furalpropenic acid.....	0.07	3.3

Still another group of suitable substances are aliphatic acids such as di-n-butylmalonic acid, di-n-propylmalonic acid and 2-butenoic acid.

Higher homologs move further away from the optimum until they are finally outside the acid factor range.

Structural Formula	Name	Lipoid	pH Acid Factor
	di-n-butylmalonic acid.....	0.7	2.7
	di-n-propylmalonic acid.....	1.1	1.9
	2-butenoic acid.....	0.001	2.4

Table I

Structure	Name	Lipoid	pH Acid Factor	Clinical Activity
	Phthalic acid.....	44.	2.3	None.
	Methyl acid phthalate.....	.24	2.0	Fair.
	n-Propyl acid phthalate.....	.001	2.4	Excellent.
	n-Butyl acid phthalate.....	.004	2.9	Very good.

Compositions of this invention may contain, in addition to the film-forming vehicle and the keratin exfoliating acid, other ingredients such as inert diluents and fillers.

The film-forming vehicle may be a silicone conforming with the structural formula:

where R is a hydrocarbon radical.

Preferably silicones having viscosities in excess of 10^2 centistokes and up to 10^6 centistokes are useful. The preferred silicones are the lower alkyl silicones such as methyl, butyl and amyl but aryl silicones such as benzyl silicone, and alkyl aryl silicones such as methyl phenyl silicone, may be used.

Where the vehicle is a silicone, the proportions for corn and callus treatment preferably lie within the ranges by weight, from 2% to 80% agent, from 0% to 78% filler, and from 20% to 70% silicone. Whenever the preparation is to be used for keratin exfoliation on portions of the body other than the foot, however, compositions containing silicone in amounts as high as 99.5% by weight may be utilized to advantage.

Where preparations of this invention use film-forming vehicles of plasticized rubber or petrolatum or other popular film-forming vehicles for salicylic acid such as lanolin, collodion, oils and waxes and ethylene glycol, methylene glycol, propylene glycol and polyethylene glycol (known to the trade as Carbowax), the percentage by weight of the exfoliating agent may, in general, be 0.5% and up, of the total composition, any given percentage being dictated, for the most part, by the condition treated and the degree of exfoliating desired. Percentages of exfoliative agent in excess of 40% have not been found appreciably to increase the effectiveness of compositions. For maximum exfoliation, therefore, any higher percentage consistent with the desired physical characteristics of the composition may be used, it being understood that additional agent decreases the plasticity and cohesiveness of the composition.

For corn and callus treatment, I prefer that the compositions have a doughy consistency to spread. Com-

positions of such consistency are most suitable for mounting on fibrous or non-fibrous backing materials, e. g., in the form of small slices cut from extruded slugs assembled with shaped cushioning materials on adhesive backing strips to form corn and callus treatment units in known manners. For this purpose I find silicone vehicles particularly useful, with plasticized rubber and petrolatum being next preferred vehicles in that order. Certain film-forming vehicles should or can be carried in a volatile diluent, for example an alcohol, ether, or ketone—common examples being collodion, or other volatile diluent carried film-forming cellulose derivatives, or vinyl polymers or co-polymers. Any of the vehicles may be modified with compatible plasticizers or softeners.

The film-forming vehicles of compositions of this invention are preferably, like those above named, non-toxic to the skin in the absence of the active ingredient or ingredients of the composition and, as is obvious, should be of such pH and non-reactivity (or limited reactivity) towards the agent as to insure the presence in the composition of sufficient free keratin-exfoliating acid, when the agent is used in the proportions herein specified, to permit gradual release of the acid from the vehicle after the composition has been applied to the skin.

Salve-like preparations of this invention with silicone or ointment bases may be preferred by some for all exfoliative purposes but they are best suited for application to portions of the skin surface not subject to the pressure, friction and temperatures usually associated with foot applications.

Compositions of this invention comprising the vehicle and the exfoliating agent and with or without fillers may vary from very light quick drying or non-drying liquid solutions and dispersions of film-forming materials and agents to substantially non-drying salve-like compositions ranging in viscosity from 10^2 up through and above 10^6 centistokes at 70° F. and including on up to doughy conformable semi-solid compositions, the viscosities of which are too high for easy centistoke determination but which have plasticities from 30 to 160 at 40° C. as measured on the Williams Plastometer. Viscosities and plasticities within this range may be controlled by the relative proportions of the vehicle and

agent, by the choice of the viscosity of the vehicle, by the addition of varying kinds and amounts of fillers, or by combinations of these methods.

Any suitable inert filler may be used in preparations of this invention, though I prefer starch or other water-swellable materials such as kaolin, wood flour, talc, zein and clays such as bentonite. Water-soluble fillers can be, for example, gum arabic or sodium carboxymethylcellulose. Useful relatively water-insoluble fillers include magnesium silicate, aluminum silicate, calcium silicate, sulfur, diatomaceous earth and asbestos.

If it is desirable, a local anesthetic may be added to the preparations of this invention without changing their general physical properties or keratin exfoliative activity appreciably. For instance, that anesthetic popularly known as dibucaine or percaine and which has the chemical name butyloxy-cinchoninic acid diethyl-ethylene diamine hydrochloride may be added, preferably to about 1% of the total weight of the other ingredients.

As illustrative of the compositions of the invention suitable for various keratin exfoliative purposes the following are given, percentages by weight:

Example 1

	Per cent
Phenoxyethanoic acid	20
Collodion	80

Example 2

	Per cent
Phenoxyethanoic acid	30
Plasticized rubber	70

Example 3

	Per cent
Phenoxyethanoic acid	40
Silicone (methyl silicone, 30,000 centistokes)	30
Starch	30

Example 4

	Per cent
Phenylmercaptoethanoic acid	30
Lanolin	70

Example 5

	Per cent
2-phenoxypropanoic acid	20
Lanolin	14
White wax	4
White petrolatum	62

Example 6

	Per cent
2-chlorophenoxyethanoic acid	.5
White petrolatum	99.5

Example 7

	Per cent
2-fluorobenzoic acid	25
Lanolin	30
White petrolatum	45

Example 8

	Per cent
n-Butyl acid phthalate	39
"Aquaphor," Duke Lab.:	
Oxycholesterol	3.6
Petrolatum	57.4

Example 9

	Per cent
2-methylbenzoic acid	15
Hydrosorb, Abbott Laboratories (fatty acid ester of diethanolamine mixed with petrolatum)	85

Example 10

	Per cent
Thiophene-2-carboxylic acid	10
Stearyl alcohol	9
Liquid petrolatum	9
Water	9
Petrolatum light	63

Example 11

	Per cent
Di-n-butylmalonic acid	20
Talc	20
Petrolatum	40
Zinc oxide	20

Example 12

	Per cent
Phenylmercaptoethanoic acid	32
Oil of cade	20
Castor oil	16
Ethyl alcohol	32

Example 13

	Per cent
2-butenoic acid	8
Polyethylene glycol (Carbowax 1580)	92

Example 14

	Per cent
Diphenoxylate	40
Silicone (methyl silicone, 1,000 centistokes)	25
Starch	35

Compositions containing some of the phenoxy and phenylmercapto aliphatic acids herein described are disclosed in my copending application Serial No. 205,436, filed January 10, 1951.

It should be understood that I do not regard the invention hereof as limited other than by the claims to compositions containing any particular keratin exfoliating agent.

I claim:

1. A keratin exfoliative composition comprising an admixture of a substantially non-volatile non-toxic viscous organic film-forming vehicle and, as an active exfoliating agent, an organic acid selected from the group consisting of aromatic acids having more than 7 carbon atoms, heterocyclic acids and mono- and di-carboxylic aliphatic acids, which have acid factors of from 1.5 to 3.5 and lipoid coefficients not greater than 5, said agent being included in said composition in an amount providing as free acid from 0.5 to 80% by weight based upon the total weight of the non-volatile ingredients of said composition.
2. A keratin exfoliative composition as claimed in claim 1, wherein the organic acid is an aromatic acid having more than 7 carbon atoms and an acid factor of from 1.5 to 3.5 and a lipoid coefficient not greater than 5.
3. A keratin exfoliative composition as claimed in claim 2, wherein the aromatic acid is an ether linked aryl acid.
4. A keratin exfoliative composition as claimed in claim 2, wherein the aromatic acid is a phenoxy aliphatic acid.
5. A keratin exfoliative composition as claimed in claim 2, wherein the aromatic acid is a phenylmercapto aliphatic acid.
6. A keratin exfoliative composition as claimed in claim 2, wherein the aromatic acid is a phthalic acid ester.
7. A keratin exfoliative composition as claimed in claim 1, wherein the organic film-forming vehicle is plasticized rubber.
8. A keratin exfoliative composition as claimed in claim 1, wherein the organic acid has an acid

factor of from about 2.1 to 2.5 and a lipoid coefficient of 0.001 to 0.4.

9. A keratin exfoliative composition comprising an admixture of a substantially non-volatile non-toxic organic film-forming vehicle, a volatile liquid organic diluent for said vehicle, and, as an active exfoliating agent, an organic acid selected from the group consisting of aromatic acids having more than 7 carbon atoms, heterocyclic acids and mono- and di-carboxylic aliphatic acids, which have acid factors of from 1.5 to 3.5 and lipoid coefficients not greater than 5, said agent being included in said composition in an amount providing as free acid from 0.5 to 80% by weight based upon the total weight of the non-volatile ingredients of said composition and said composition having a viscosity less than 160 plasticity at 40° C. as measured on a Williams Plastometer.

10. A pharmaceutical product for corn and callus treatment comprising an adhesive backing strip bearing a shaped cushioning material and a composition of doughy conformable semi-solid consistency, said composition comprising an admixture of a substantially non-volatile non-toxic viscous organic film-forming vehicle, a finely divided inert filler, and, as an active exfoliating agent, an organic acid selected from the group consisting of aromatic acids having more than 7 carbon atoms, heterocyclic acids and mono- and di-carboxylic aliphatic acids, which have acid factors of from 1.5 to 3.5 and lipoid coefficients not greater than 5, said agent being included in said composition in an amount providing as free acid from 0.5 to 80% by weight based upon the total weight of the non-volatile ingredients of said composition.

11. A keratin exfoliative composition comprising an admixture of a substantially non-volatile non-toxic viscous organic film-forming vehicle, and, as an active exfoliating agent, phenoxyethanoic acid in an amount providing as free acid from 0.5 to 80% by weight based upon the total weight of the non-volatile ingredients of said composition.

12. A keratin exfoliative composition comprising an admixture of plasticized rubber and, as an active exfoliating agent, phenoxyethanoic acid in an amount providing as free acid from 0.5 to 80% by weight based upon the total weight of the non-volatile ingredients of said composition.

13. A keratin exfoliative composition comprising an admixture of a substantially non-volatile non-toxic organic film-forming vehicle, a volatile liquid organic diluent for said vehicle, and, as an active exfoliating agent, phenoxyethanoic acid in an amount providing as free acid from 0.5 to 80% by weight based upon the total weight of the non-volatile ingredients of said composition, said composition having a viscosity less than 160 plasticity as measured on a Williams Plastometer.

14. A pharmaceutical product for corn and callus treatment comprising an adhesive backing strip bearing a shaped cushioning material and a composition of doughy conformable semi-solid consistency, said composition comprising an admixture of a substantially non-volatile non-toxic viscous organic film-forming vehicle, and, as an active exfoliating agent, phenoxyethanoic acid in an amount providing as free acid from 0.5 to

80% by weight based upon the total weight of the non-volatile ingredients of said composition.

15. A keratin exfoliative composition comprising an admixture of a substantially non-volatile non-toxic viscous organic film-forming vehicle, and, as an active exfoliating agent, phenylmercaptoethanoic acid in an amount providing as free acid from 0.5 to 80% by weight based upon the total weight of the non-volatile ingredients of said composition.

16. A keratin exfoliative composition comprising an admixture of a substantially non-volatile non-toxic viscous organic film-forming vehicle, and, as an active exfoliating agent, 2-phenoxybutanoic acid in an amount providing as free acid from 0.5 to 80% by weight based upon the total weight of the non-volatile ingredients of said composition.

17. A keratin exfoliative composition comprising an admixture of a substantially non-volatile non-toxic viscous organic film-forming vehicle, and, as an active exfoliating agent, n-propyl acid phthalate in an amount providing as free acid from 0.5 to 80% by weight based upon the total weight of the non-volatile ingredients of said composition.

18. A keratin exfoliative composition as claimed in claim 1, wherein the organic acid is a heterocyclic acid having an acid factor of from 1.5 to 3.5 and a lipoid coefficient not greater than 5.

19. A keratin exfoliative composition comprising an admixture of a substantially non-volatile non-toxic viscous organic film-forming vehicle, and, as an active exfoliating agent, thiophene-2-carboxylic acid in an amount providing as free acid from 0.5 to 80% by weight based upon the total weight of the non-volatile ingredients of said composition.

20. A keratin exfoliative composition as claimed in claim 1, wherein the organic acid is a di-carboxylic acid having more than 7 carbon atoms and an acid factor of from 1.5 to 3.5 and a lipoid coefficient not greater than 5.

21. A keratin exfoliative composition as claimed in claim 1, wherein the organic acid is a mono-carboxylic acid having more than 7 carbon atoms and an acid factor of from 1.5 to 3.5 and a lipoid coefficient not greater than 5.
